ELECTRONIC TUBE

William W. Eitel, San Bruno, and Jack A. McCullough, Millbrae, Calif., assignors to Eitel-McCullough, Inc., San Bruno, Calif., a corporation of California

Application July 13, 1942, Serial No. 450,755

1 Claim. (Cl. 250—27.5)

Our invention relates to an electronic tube particularly adapted for transmission purposes.

It is among the objects of our invention to provide an improved structure of, arrangement for and mounting of the electrodes and leads in the envelope of a tube.

Another object is to provide an electrode mounting which protects the glass seal about a lead from cracking under heat originating at the electrode.

The invention possesses other objects and features of advantage, some of which, with the foregoing, will be set forth in the following description of our invention. It is to be understood that we do not limit ourselves to this disclosure of species of our invention, as we may adopt variant embodiments thereof within the scope of the claim.

Referring to the drawings:

Figure 1 is a perspective view of a tube embodying the improvements of our invention; and

Figure 2 is a vertical sectional view of the same.

Figure 3 is a fragmentary perspective view showing a modified plate support.

In terms of broad inclusion, our tube comprises an envelope having a reentrant stem at one end thereof. A plurality of electrodes including a plate, and grid and cathode are arranged in the envelope. The cathode leads are sealed to the stem; the plate lead to the opposite end of the envelope; and the grid lead to a side wall. Improved means are provided for mounting the plate; and improved means are further provided for protecting the envelope from cracking at the lead seals.

In greater detail, and referring to the drawings, our tube comprises an envelope of glass or the like having a bulb-shaped body 2 terminating at the top in a reduced neck 3 and at the bottom in a larger neck 4 carrying a reentrant stem 6 having an exhaust tubulation 7. The envelope is fitted with a cup-shaped base 8 of metal having a bottom disk 9 of porcelain carrying prongs 11. This base is secured to neck 4 by a suitable cement 12.

Within the envelope are disposed a plurality of coaxial electrodes including a cathode 13, grid 14 and plate or anode 16. The plate is a hollow cylindrical body of suitable material, say tantalum, preferably formed of sections having flanges welded together to form heat radiating fins 17. The lower end of plate 16 is open, facing stem 6. A hemispherical cap 18 of tantalum is secured to the upper end of the plate by depending tabs 19

welded to the rim. Arched recesses 21 in the cap between tabs 19 provide vent openings. This end cap forms part of the plate supporting means, and also protects the glass at the upper end of the envelope against heat and electron bombardment.

Plate lead 22 of tungsten projects thru the end of top neck 3 at seal 23 and carries an external terminal button 24. In order to stop heat from flowing out along the tungsten lead and cracking the glass at the seal, the inner end of this lead is terminated short of the electrodes, leaving a considerable spacing between the inner end of the lead and cap 18. A tubular bracket 26 of tantalum, preferably conical in shape, is interposed between the lead and cap, with its converging end welded to the lead and its diverging end welded to the cap. This conical bracket on the dome of the hemispherical cap provides a strong mounting having sufficient rigidity to hold the plate in proper alignment even under severe jarring of the tube.

The thin walls of the tubular bracket augment the heat radiating surface provided by cap 18, so that both bracket and cap cooperate to thermally insulate the lead and its seal 23 from the heat zone at the plate. The heat that tends to flow by conduction toward seal 23 is thus largely dissipated by radiation before it reaches lead 22. Our improved structure overcomes the problem of cracked seals so bothersome in tubes where a lead is brought in close to the heat zone at the electrodes.

Grid 14 is of the cage type, preferably of platinum wire, terminating in a tantalum base ring 27. This electrode is supported by a bracket 28 on a lead having an upturned portion 29 and a transverse portion 31 projecting thru the side of the envelope at seal 32; the latter seal being preferably formed in the cylindrical wall of neck 4. Bracket 28 is made of a strip of tantalum bent around lead portion 29 and having diverging ends lying alongside grid ring 27. These parts are secured by welding. In order to protect seal 32 against excessive heating a metallic disk 33 is disposed transversely on the lead to shield the seal. Tab 34, formed as a knock-out when the disk aperture is made, is conveniently welded to the lead.

Cathode 13 preferably comprises a pair of hairpin filaments of thoriated tungsten having the lower ends secured to a pair of leads 36 sealed in press 37 of stem 6. The upper ends of the filaments are hooked over a cross piece 38 slideable on a central standard 39; the filament wires

being held under tension by a spring 41 encircling the standard and bearing against a sleeve 42 engaging under cross piece 38.

Since stem 6 faces the lower open end of plate 16, and is subject to considerable heat and electron bombardment, a cup-shaped metallic shield 43 is arranged over the end of the stem. The shield is provided with openings in the top, thru which cathode leads 36 project. Connection between central standard 39 and the shield is effected by tabs 44 welded to the parts.

Figure 3 shows a modified plate mounting in which the bracket has an elongated tubular core 46 with longitudinally extending fins 47. This will dissipate more heat than the structure first described, and is adaptable for larger tubes. Because the tubular bracket lies between the end of lead 48 and cap 49 it cooperates with the latter to thermally isolate the lead from plate 51. The lower portion of the bracket is preferably made of tantalum, with outturned tabs 52 welded to the dome of cap 49. This joint is easily made

as tantalum welds readily to tantalum. A tantalum to tungsten weld is more difficult to make however, so we prefer to form the upper portion of the bracket of nickel. Nickel welds nicely with both the other two metals, producing strong clean joints. The welding problem is taken care of in the structure first described by means of a nickel sleeve 54 interposed between the lead and bracket.

We claim:

10 An electronic tube comprising an envelope having a reentrant stem at one end thereof, a hollow plate in the envelope having an open end facing the stem, means interposed between the plate and stem for shielding the stem against heat and electron bombardment from the open end of the plate, a cap on the other end of the plate, a lead sealed to the envelope, means supporting the plate on said lead, a cathode adjacent the plate, and leads for the cathode sealed to the stem.
